A. LICHT

MITTEN AND GLOVE HANGER

Filed June 14, 1924

Inventor

Arthur Licht

By Watson E. Coleman
Attorney

UNITED STATES PATENT OFFICE.

ARTHUR LICHT, OF FULTON, SOUTH DAKOTA.

MITTEN AND GLOVE HANGER.

Application filed June 14, 1924. Serial No. 719,998.

To all whom it may concern:

Be it known that I, ARTHUR LICHT, a citizen of the United States, residing at Fulton, in the county of Hanson and State of South Dakota, have invented certain new and useful Improvements in Mitten and Glove Hangers, of which the following is a specification, reference being had to the accompanying drawings.

10 This invention relates to means for supporting articles, and particularly to a device for supporting mittens and gloves.

15 The object of the invention is to provide a very simple clamp-like device which is adapted to be attached to a wall and which will support mittens or gloves either for display in shop windows or in dressing rooms.

20 A further object is to provide a device of this character which is very simple, which may be formed of one length of wire, which may be swung up against the wall when not in use, and which will support the mittens and gloves or like articles in position.

25 My invention is illustrated in the accompanying drawings, wherein:—

Figure 1 is a perspective view of my device in applied position;

Figure 2 is a vertical sectional view of the same;

30 Figure 3 is a top plan view;

Referring to these drawings, it will be seen that my device is formed of a single length of wire. This wire is bent so as to provide the two upwardly extending spaced loops 10, the legs of these loops extending vertically and the inside legs, that is the adjacent legs, being joined by the cross wire 11. The outer legs extend downward to a point approximately even with the cross bar

35 11 and then extend directly outward, as at 12, assuming that the device is in position for use. Each of these outwardly extending portions 12 is bent upward, as at 13, and then inwardly extended, as at 14, and these

40 45 portions 14 are slightly outwardly bowed away from each other and are disposed, of course, on a higher level than the portions 12. These outwardly bowed portions 14 are connected at 15.

50 The device is adapted to be supported against the wall A by any suitable means

and preferably by U-shaped fastening devices as, for instance, by double-pointed tacks or clips 16. Of course, it is obvious that the device might be applied to a panel, 55 which in turn would be mounted upon a wall in any suitable manner or applied to a door or cabinet. The device may be turned up when out of use or it may be permanently fastened so as to project outward. The 60 gloves, mittens or other articles may be clamped between the portions 14 or may be disposed horizontally upon the legs 12 and beneath the portions 14. The device is also adapted for use in restaurants, theatres and 65 the like for holding gloves and like articles.

This device is particularly intended for use as a holder for gloves or mittens which are ordinarily thrown down and, therefore, readily get lost in such a way as to make 70 them difficult to find. My device is intended to be nailed or otherwise attached to a wall beneath the coat hanger or in a closet or dressing room so that there always will be a place to put the mittens or gloves when 75 the coat is taken off.

I claim:

A glove and mitten holder of the character described formed of a single length of wire bent to provide a wall-engaging portion consisting of two upwardly extending, U-shaped bights disposed in spaced relation to each other and constituting means for attachment to a wall, the bights being connected at their lower ends by an integral cross bar and the outer arms of the bights at their lower ends being outwardly extended in a horizontal plane and convergently with relation to each other, then extending upward and then extending inward to form a middle elongated bight having somewhat bowed sides disposed in a plane sufficiently above the outwardly extending portions to permit mittens or gloves to be inserted between said outwardly extending portions and said bight, the middle elongated bight being disposed between the outwardly extending portions.

90 95 In testimony whereof I hereunto affix my signature.

ARTHUR LICHT.
